Lacy, Lacy, Attorney

UNITED STATES PATENT OFFICE.

ERNEST E. MESSLER, OF BRADLEY BEACH, AND GEORGE M. HULICK, OF ASBURY PARK,
NEW JERSEY.

POTATO-EYEING MACHINE.

Application filed June 6, 1923. Serial No. 643,654.

To all whom it may concern:

Be it known that we, ERNEST E. MESSLER and GEORGE M. HULICK, citizens of the United States, residing at Bradley Beach and Asbury Park, respectively, in the county of Monmouth and State of New Jersey, have invented certain new and useful Improvements in Potato-Eyeing Machines, of which the following is a specification.

This invention has for its object the provision of a very simple, efficient and inexpensive tool for domestic use whereby eyes may be removed from potatoes. The invention provides a device which will not require any manual manipulation by the user who needs only to hold the potato against the working part of the device. The invention is illustrated in the accompanying drawing and will be hereinafter fully set forth.

In the drawing:

Figure 1 is a view, partly in side elevation and partly in vertical section, of an apparatus embodying our invention, and

Fig. 2 is a front elevation of the same. In the drawing, the reference numeral 1 indicates a table or other support upon which is rigidly secured a bracket 2 adapted to support an electric motor 3 which may be of any standard type and which may be employed for other purposes when not needed in the practice of our invention. The motor shaft, indicated at 4, has secured thereto, in any convenient manner, a shank 5 carrying at its outer end a bit 6 which is preferably of tapered or conical form, as shown, having two radially alined cutting edges and spaced but adjacent entering points. Disposed about the said bit is a housing 7 having a vertical back wall 8 which fits closely about the motor shaft 4 and having a longitudinally extending wall of arched form, as clearly shown in Fig. 2, the entire front of this housing being open and the housing being secured upon the table 1 in any convenient or preferred manner.

In using the device, the operator holds the potato in such position that the eye to be removed will be in contact with the points of the bit 6 and presses the potato against the said bit as the latter rotates. The eye will be very quickly cut out from the body of the potato and any juices which may be liberated will be splashed against the walls of the housing 7 and will be thereby prevented from spattering upon the clothes or hands of the user. The device will operate very quickly and will consume a very small quantity of current inasmuch as the motor may be very small and, in fact, may be of a type driven by water power or other source of energy.

Having thus described the invention, what is claimed as new is:

1. In a vegetable corer, a rotary bit having two cutting edges diametrically alined, said cutting edges being of conical shape having their apices spaced apart and situated in the diametrical plane of the cutting edges.
2. In a vegetable corer, a rotary bit having two cutting edges diametrically alined, said cutting edges being obtained by splitting a cone-shaped bit along an axial plane and spacing the apices of the two cone halves, so formed, apart in said axial plane.
3. In a vegetable corer, a rotary bit having two cutting edges diametrically alined, said cutting edges being obtained by splitting a cone-shaped bit along an axial plane and spacing the apices of the two cone halves, so formed, apart in said axial plane, an open-front housing surrounding said bit, said bit having positive connection with a prime mover.

In testimony whereof we affix our signatures.

ERNEST E. MESSLER. [L. S.]
GEORGE M. HULICK. [L. S.]
